UNITED STATES PATENT OFFICE.

HERMAN CASLER, OF SYRACUSE, N. Y.

DESIGN FOR A CAMERA-CASE.

SPECIFICATION forming part of Design No. 22,649, dated July 25, 1893.

Application filed March 13, 1893. Serial No. 465,816. Term of patent 7 years.

To all whom it may concern:

Be it known that I, HERMAN CASLER, a citizen of the United States, residing at Syracuse, county of Onondaga, and State of New York, have invented and produced a new and original Design for Camera-Cases, of which the following is a description, reference being had to the accompanying drawings, in which—

Figure 1, is a front view of my design for a camera case. Fig. 2, is an edge view thereof.

The leading feature of my design consists in a circular camera case, its rear end terminated abruptly and its front face slightly graduated from the main body until it reaches the front face.

A, is the body of the case which is circular in its general contour, and —a— is its rear face, and —b— is its front face.

B, is a post; and —C— is the ring secured therein. The irregular outline of its edge ²⁰ view, in contrast with the symmetrical circular contour of its front view, presents to the eye a pleasing effect.

What I claim, and desire to secure by Letters Patent, is—

The design for a camera case, substantially as herein described and shown.

In witness whereof I have hereunto set my hand this 6th day of March, 1893.

HERMAN CASLER.

In presence of—

HOWARD P. DENISON,
HERBERT A. CARHART.
